ATTORNEY

UNITED STATES PATENT OFFICE.

WILLIAM A. LAND, OF HEWINS, KANSAS, ASSIGNOR OF ONE-THIRD TO MARSHALL H. TAYLOR, OF HEWINS, KANSAS.

CATTLE-GUARD.

1,305,907.

Specification of Letters Patent. Patented June 3, 1919.

Application filed February 13, 1917. Serial No. 148,367.

To all whom it may concern:

Be it known that I, WILLIAM A. LAND, a citizen of the United States, residing at Hewins, in the county of Chautauqua and State of Kansas, have invented new and useful Improvements in Cattle-Guards, of which the following is a specification.

This invention relates to a cattle guard which may be employed to prevent cattle from straying along a railroad track and in which a barrier for this purpose may be raised to a vertical position by the weight of an animal upon a depressible platform connected therewith.

The primary object of the invention is to provide a cattle guard of this character which is simple in construction and may be quickly installed and in which frames serving as supports for the platforms for moving the movable barrier to an active position are of novel construction.

Another object of the invention is to provide bearing brackets which serve as a support for the movable barrier and are so constructed that they may be adjusted upon a support to which said brackets are connected to regulate the tension of springs for restoring and maintaining the movable barrier in an inactive position.

With these and other objects in view, the invention resides in the novel combination and arrangement of parts, which will be hereinafter described and particularly pointed out in the claim.

The preferred embodiment of the invention has been illustrated in the accompanying drawings, although no restriction is necessarily made to the precise details of construction therein shown, as changes, alterations, and modifications, within the scope of the claim may be resorted to when desired.

In the drawings:

Figure 1 is a top plan view of a cattle guard constructed in accordance with the invention, and showing the same mounted upon the ties of a section of railroad track.

Fig. 2 is a side elevation of Fig. 1.

Fig. 3 is a vertical longitudinal sectional view through the center gate member with the said gate in its raised position.

Fig. 4 is a detailed perspective view of one of the platform supporting frames.

Fig. 5 is a detailed perspective view of one of the bearing brackets for the gate shaft.

Like characters of reference denote corresponding parts throughout the several views in the drawings.

Referring now to the drawings in detail, the letter A designates a section of railroad track which is shown in the drawings as passing through an opening in a fence, with the ties 6 having secured thereto the track rails 7 in the usual manner.

Arranged at opposite ends of one of the ties 6 are bearing brackets 8, each of said brackets comprising a plate like body 9 for contact with an end of the tie and having formed therein a longitudinally extending slot 10, one wall of which has formed thereon spaced teeth 11 between which may be arranged headed spikes 12 passing through the slot 10 and driven into the ends of the tie to secure the bearing bracket thereto. Formed on the body 9 at one corner thereof is a bearing sleeve 13.

By connecting the bearing brackets with the ends of the tie as above described, it will be seen that the bearing brackets may be adjusted transversely of the tie when the occasion requires for a purpose which will hereinafter appear.

A gate 14 to be supported upon the tie 6 to which the bearing brackets 8 are connected when the gate is in an inactive position has a rail 15 thereof arranged between said tie and the tie adjacent thereto with the ends of the rail provided with trunnions 16 received in the bearing sleeves 13 on the brackets 8. Spaced bars 17 are connected with the rail 15 which is provided with spaced recesses 18 and 19, the recesses 18 receiving therein the bases of the track rails while the recesses 19 have passed therethrough flexible members 20 each of which has one terminal thereof connected with the rail 15 of the gate.

Spaced yokes 21 arranged adjacent to and between the track rails 7 and formed from angle iron have the connecting bars 22 for the arms 23 thereof hingedly connected with one of the ties 6 by bearing plates 24, the free ends of the arms of the yokes having formed thereon eyes 26 through which are passed the other ends of the flexible elements 20, the length of said elements being such that the weight of the gate is sufficient to normally hold the yokes raised above the ties positioned therebeneath. The arms 23 of the yokes are offset adjacent their free ends.

to form shoulders 27 which when the yokes are depressed engage with the side of one of the ties 6 and limit the downward movement of the yokes.

5 Arranged upon each yoke 21 is a platform 28 formed from any suitable material such as sheet iron, or the like, and is removably connected with the yoke by fingers 29 at the sides of the platform which may be engaged with the flanges on the arms of the yoke upon which the platform is supported.

Connected with the rail 15 of the gate and with the face of the tie 6 with which the shoulders on the yokes are adapted to contact when the yokes are depressed is a coiled spring 30 which serves to restore the gate to an inactive position when raised by a weight disposed on one or more of the platforms 28.

When the improved guard is mounted 20 upon the ties of a railroad track as shown in Fig. 1 in the drawings, and an animal steps upon one of the platforms 28, the weight of the animal will depress the platform and cause the same to swing the gate 14 to a vertical position as shown in Fig. 3 in the drawings at which time, the stop shoulders 27 on the arms of the yokes will contact with a face upon one of the ties and prevent further turning movement of the gate toward the platforms.

When the animal steps from the platform upon which it has been standing, the spring 30 serves to move the gate 14 and the platforms to their normal position, the bars 35 upon the rail 15 through their contact with the tie to which the bearing brackets are connected serving to limit the turning movement of the gate in this direction.

In order that the tension of the springs 30

may be controlled the bearing brackets may 40 be adjusted on the ends of the ties 6 as above described.

From the foregoing statements, taken in connection with the accompanying drawings, it is at once apparent that a cattle 45 guard has been provided which is highly efficient in use, comparatively simple in construction, and easy to install.

Having thus described the invention, what is claimed as new, is:

In combination with a railway track, a gate therefor and a depressible platform having a flexible connection with the gate and designed when pressure is exerted thereon to swing the gate to one position, and means for normally retaining the gate in another position, said gate having outwardly extending trunnions at the bottom thereof, brackets, sleeves formed on one of the corners of each of the brackets receiving the 60 trunnions of the gate, the body of each of the brackets having a longitudinally extending slot, the upper wall of the said slot having spaced teeth and the body of each of the brackets designed to be arranged in contacting engagement with the ends of one of the supporting ties for the track, and securing elements embedded in the ends of the tie and passing through the slots in the brackets whereby certain of said securing 70 elements are received between the teeth of the brackets and others contacting with the lower walls provided by the slots, whereby said brackets are sustained adjusted both longitudinally and angularly on the ends of 75 the tie.

In testimony whereof I affix my signature.

WILLIAM A. LAND.
